(57) **CLAIM**

The ornamental design for a cellular module as shown and described.

DESCRIPTION

FIG. 1 is a bottom view of the claimed design for a cellular module according to a first embodiment;

FIG. 2 is a perspective view thereof;

FIG. 3 is a left side view thereof;

FIG. 4 is a top view thereof;

FIG. 5 is a front view thereof;

FIG. 6 is a rear view thereof;

FIG. 7 is a right side view thereof;

FIG. 8 is a bottom view of the claimed design for a cellular module according to a second embodiment;

FIG. 9 is a perspective view thereof;

FIG. 10 is a left view thereof;

FIG. 11 is a top view thereof;

FIG. 12 is a front view thereof;

FIG. 13 is a rear view thereof;

FIG. 14 is a right side view thereof

FIG. 15 is a bottom view of the claimed design for a cellular module according to a third embodiment;

FIG. 16 is a perspective view thereof;

FIG. 17 is a left view thereof;

FIG. 18 is a top view thereof;

FIG. 19 is a front view thereof;

FIG. 20 is a rear view thereof; and,

FIG. 21 is a right side view thereof.

The outermost solid lines in FIGS. 1, 8, and 15 depict claimed boundaries of the claimed design. The broken lines showing the remainder of the cellular module depict environmental structure and form no part of the claimed design.

(Continued)

Portions of the cellular module not shown in the drawing form no part of the claimed design.
